Application August 9, 1940, Serial No. 351,922

14 Claims.

(Cl. 250—27)

The present invention relates to electron discharge devices and more particularly to thermionic vacuum tubes such as are employed in the radio art, and to circuit arrangements therefore.

The main object of this invention is to decrease the cathode heating time of thermionic vacuum tubes for normal electron emission, so that proper cathode heating is secured in a fraction of the time required at present.

Other objects and advantages of this invention will appear as the specification proceeds.

It is well known that when a radio receiver or similar electron discharge apparatus is switched on, an interval of time elapses before it begins to function, due to the time interval required for the cathodes of the thermionic vacuum tubes to attain the temperature necessary for normal electron emission.

Thermionic vacuum tubes have two types of cathodes, the directly heated cathode and the indirectly heated cathode. In the directly heated cathode type of thermionic vacuum tube, a filament heated by the flow of electric current through it supplies the electrons. The filament may consist of tungsten, thoriated tungsten, or of a metal coated with electron-emitting material. In the indirectly heated cathode type of thermionic vacuum tube, a heater usually made of tungsten or tungsten-alloy wire is enclosed within a metallic cathode sleeve coated with electron-emitting material. The heater is supplied with electric current, and heats the coated metallic cathode sleeve which supplies the electrons.

In the case of radio receiving tubes, the time interval required for cathode heating to produce normal electron emission is generally quite short for the directly heated cathode type, but is considerably longer for the indirectly heated cathode type.

The present invention sets forth cathode heating arrangements for thermionic vacuum tubes which greatly reduce the cathode heating time required to attain normal electron emission, so that radio receivers and similar electron discharge apparatus when switched on, begin to function in a fraction of the time required at present. In experiments performed, radio receivers using some of the cathode heating arrangements set forth in this invention, and employing both indirectly and directly heated cathode type tubes of present day manufacture, attained full signal volume in two to four seconds after being switched on. These results may be improved upon, if the thermionic vacuum tubes

employed are constructed to facilitate rapid cathode heating.

Decrease of the cathode heating time for normal electron emission of the indirectly heated cathode type of thermionic vacuum tube is accomplished by the following two methods:

1. By applying a voltage greater than normal or rated voltage to the heater of the thermionic vacuum tube until the cathode is brought to the proper temperature for normal electron emission, after which normal or rated voltage is applied to the heater. The application of greater than normal voltage to the heater of the thermionic vacuum tube results in greater than normal flow of current through the heater and therefore in rapid heating of the cathode.

2. By providing two separate heaters or a double-heater within the metallic cathode sleeve of the thermionic vacuum tube, one used for normal heating of the cathode, and the other which produces more heat is used for rapid heating of the cathode, both heaters being switched on at the same time, and when the cathode attains the proper temperature for normal electron emission, the heater which causes rapid cathode heating is switched off, and the cathode is thereafter heated only by the one causing normal heating.

Decrease of the cathode heating time for normal electron emission of the directly heated cathode type of thermionic vacuum tube is accomplished by the first method. In the case of radio receiving tubes, the directly heated cathode type heats up quite rapidly, so that it is necessary to apply rapid filament heating only for the larger sizes of tubes.

In the application of the first method to effect rapid cathode heating, the greater than normal voltage applied to the filaments or heaters of thermionic vacuum tubes is generally from two to several times greater than normal or rated voltage, the directly heated cathode type requiring a lower value than the indirectly heated cathode type, for tubes of equal rating.

45 The accompanying drawings forming a material part of this disclosure, together with the description serve to explain the principles of the invention.

50 Of the drawings:

Figures 1 to 6 are schematic diagrams of the heater and filament circuits of the thermionic vacuum tubes of radio receivers or other electron discharge apparatus, showing means for securing rapid cathode heating for normal electron emission.

The elements or electrodes of the thermionic vacuum tubes not necessary for explanatory purposes have been omitted to simplify the diagrams.

The various arrangements for securing rapid cathode heating of thermionic vacuum tubes employed in radio receivers and other electron discharge apparatus will now be described in detail, with the aid of the drawings.

In Fig. 1, the heating elements or filaments 1 of the directly heated cathode type thermionic vacuum tubes 2 are connected in series across the voltage supply circuit terminals 6 and 7 through voltage-dropping resistors 4 and 5 which are in parallel when main switch 8 is closed. This allows the application of greater than normal voltage to the filaments 1 of the thermionic vacuum tubes 2, resulting in rapid filament heating. When normal electron emission is attained by the filaments 1, plate current flows through the coil 20 of relay 17 connected in the plate circuit of one of the thermionic vacuum tubes 2, in which the plate is denoted by 11, thereby attracting armature 21 and thus opening the circuit through resistor 5 and also the filament circuit of a thermionic time-delay tube 28 which prevents a safety relay 26 connected in its plate circuit from operating. The plate of the thermionic time-delay tube 28 is denoted by 12. Only resistor 4 remains in the filament circuit of the thermionic vacuum tubes 2 thereafter, allowing the application of normal voltage to the filaments 1, resulting in normal heating of the filaments.

The safety relay 26 which is of the self-locking hand-reset type, automatically opens the circuit through resistor 5, should relay 17 fail to operate when the thermionic vacuum tubes 2 attain normal electron emission, because of trouble either in the apparatus or relay proper, thereby preventing damage to the filaments or other elements of the thermionic vacuum tubes 2.

Substantially normal filament voltage is applied to the filament 29 of the thermionic time-delay tube 28 by means of a step-down transformer 30. The exact time of operation of the safety relay 26 is accurately adjusted by the rheostat 31 in the filament circuit of the thermionic time-delay tube 28, or by the variable resistor 33 shunted across the relay coil 27.

The plate voltage for the thermionic time-delay tube 28 is taken directly from the voltage supply circuit so that it is independent of any rectifier or filter circuits, and is not affected by faults in these circuits which might cut off the plate voltage and thus prevent safety relay 26 from operating when necessary.

The thermionic time-delay tube 28 and the safety relay 26 connected in its plate circuit, together constitute a thermionic time-delay relay which opens the circuit through resistor 5 at the end of a predetermined time interval after the closing of main switch 8, should relay 17 fail to operate, this time interval being somewhat longer than that required for the rapid filament heating of the thermionic vacuum tubes 2. The thermionic time-delay tube 28 is of a type that attains substantially normal electron emission in approximately the required time interval, and is of the directly heated cathode or filament type, because this type of cathode can attain substantially normal electron emission in the short time interval required.

When relay 17 opens the circuit through resistor 5 on completion of rapid filament heating of the thermionic vacuum tubes 2, the attraction

of its armature 21 also opens the filament circuit of the thermionic time-delay tube 28 somewhat before this tube attains substantially normal electron emission, thereby preventing safety relay 26 connected in its plate circuit from operating.

Should relay 17, however, fail to operate when normal electron emission is attained by the thermionic vacuum tubes 2 subjected to rapid filament heating, because of some fault in the apparatus or relay, the thermionic time-delay tube 28 at the end of a predetermined time interval after the closing of main switch 8 attains substantially normal electron emission, and the resulting flow of plate current through the coil 27 of safety relay 26 causes the attraction of armature 24, thereby opening the circuit through resistor 5 and thus preventing damage to the thermionic vacuum tubes 2. When the failure of relay 17 to operate has been investigated and the trouble remedied, safety relay 26 which has been locked in its open position is reset by hand.

In this circuit arrangement, the thermionic time-delay tube 28 draws filament current only for a very short time interval when main switch 8 is closed, until relay 17 operates and opens its filament circuit.

The circuit arrangement shown may be altered so that relay 17 opens the plate circuit of the thermionic time-delay tube 28 instead of its filament circuit, to prevent safety relay 26 from operating.

Safety relay 26 also prevents continuous rapid filament heating of the thermionic vacuum tubes 2, should armature 21 of relay 17 cease to be attracted during the operation of the radio receiver or other electron discharge apparatus, due to some fault. When armature 21 ceases to be attracted, it closes the circuit through resistor 5 causing rapid filament heating of the thermionic vacuum tubes 2, but it also closes the filament or plate circuit (whichever is the case) of the thermionic time-delay tube 28, resulting in the flow of plate current through the coil 27 of safety relay 26, thereby attracting armature 24 and thus opening the circuit through resistor 5 and preventing damage to the thermionic vacuum tubes 2. When the trouble is remedied, safety relay 26 is reset by hand.

The terminal 34 of relay coil 20 in relay 17 may be supplied either with filtered D. C. voltage or with voltage taken directly from the voltage supply circuit.

Fig. 2 differs from Fig. 1 only in that relay 17 is connected in the plate circuit of a thermionic time-delay tube 28' instead of in the plate circuit of one of the thermionic vacuum tubes 2 subjected to rapid filament heating. The plate of this thermionic time-delay tube 28' is denoted by 12', its filament by 29', and the rheostat in its filament circuit by 31'. The filament 29' of the thermionic time-delay tube 28' is supplied with voltage by the same transformer 30 that supplies filament voltage to the thermionic time-delay tube 28, in the plate circuit of which safety relay 26 is connected.

The thermionic time-delay tube 28' together with relay 17 connected in its plate circuit constitute a thermionic time-delay relay which is adjusted to operate and break the circuit through resistor 5 when the thermionic vacuum tubes 2 attain normal electron emission upon being subjected to rapid filament heating. The exact time of operation of this thermionic time-delay relay is accurately adjusted by the rheostat 31' in the

filament circuit of the thermionic time-delay tube 28', or by the variable resistor 33 shunted across the relay coil 20 of relay 17.

The terminal 34 of relay coil 20 in relay 17 may be supplied either with filtered D. C. voltage or with voltage taken directly from the voltage supply circuit.

The operation of circuit of Fig. 2 is otherwise the same as that of Fig. 1.

Figures 3 and 4 are similar to Figures 1 and 2 respectively, differing only in that the thermionic vacuum tubes 2 are of the indirectly heated cathode type provided with a cathode 3 which is heated by a heating element or heater 4. Rapid cathode heating is accomplished by the application of greater than normal voltage to the heaters 4 of the thermionic vacuum tubes 2 until normal electron emission is attained by the cathodes 3, whereupon relay 17 operates to break the circuit through resistor 5 thereby applying normal voltage to the heaters 4 to effect normal cathode heating of the thermionic vacuum tubes 2 thereafter. Otherwise, the operation of the circuits of Figures 3 and 4 is the same as that of Figures 1 and 2 respectively.

In Figures 1, 2, 3, and 4, although the filaments or heaters 4 of the thermionic vacuum tubes 2 are shown connected in series, they may also be connected in parallel.

Figures 5 and 6 are similar to Figures 3 and 4 respectively, differing only in some features. The thermionic vacuum tubes 2 are of the indirectly heated cathode type, provided with two heating elements or heaters 4 and 4' within the metallic cathode sleeve 3, the heater 4 causing normal cathode heating, and the heater 4' which produces more heat causing rapid cathode heating. The heaters 4 used for normal cathode heating are connected in parallel across the secondary 16 of a step-down transformer 15. The primary 18 of the transformer is connected across the voltage supply circuit terminals 6 and 7. The heaters 4' used for rapid cathode heating are connected in series through the voltage-dropping resistor 35 across the voltage supply circuit terminals 6 and 7. When main switch 8 is closed, voltage is applied to both sets of heaters 4 and 4', causing rapid heating of the cathodes 3 of the thermionic vacuum tubes 2. When normal electron emission is attained by the cathodes 3, relay 17 operates, opening the circuit of the set of heaters 4' used for rapid cathode heating, and also the plate circuit of the thermionic time-delay tube 28 to prevent operation of safety relay 26. Thereafter the cathodes 3 of the thermionic vacuum tubes 2 are normally heated by the set of heaters 4. Otherwise, the features and operation of the circuits of Figures 5 and 6 are the same as those of Figures 3 and 4 respectively.

In Figures 5 and 6, the sets of heaters 4 and 4' may each be connected in series or in parallel, if desired.

In Figures 1, 3, and 5, wherein relay 17 is shown connected in the plate circuit of one of the thermionic vacuum tubes 2 subjected to rapid cathode heating, this tube may perform a definite function in a radio receiver or other electron discharge apparatus besides that of operating the relay when plate current flows, or it may be used only for the purpose of operating the relay, in which case the plate voltage for the tube may be taken directly from the voltage supply circuit, so that it is independent of faults in rectifier or filter circuits.

Similarly, in Figures 2, 4, and 6, wherein relay 17 is shown connected in the plate circuit of a thermionic time-delay tube 28', this tube may perform a definite function in the radio receiver or other electron discharge apparatus besides that of operating the relay. A filament type power amplifier tube in a radio receiver, for instance, may function both as a power amplifier and as a thermionic time-delay tube to operate the relay in its plate circuit. In this case, the plate voltage for the thermionic time-delay tube must be filtered D. C. If the thermionic time-delay tube is used only for the purpose of operating the relay in its plate circuit, its plate voltage may be taken directly from the voltage supply circuit, so that it is independent of faults in rectifier or filter circuits.

Since the plate current of the thermionic time-delay tube 28 or 28' (in Figures 1, 2, 3, 4, 5, and 6) rises to a maximum or normal value relatively slowly, and the relay 26 or 17 in its plate circuit requires a certain minimum value of plate current for its operation, the time of operation of the thermionic time-delay relay (which consists of the thermionic time-delay tube and the relay in its plate circuit) may be controlled by means of a variable resistor shunted across the coil of the relay to regulate the flow of plate current through the coil.

The relay takes longest to operate when the variable resistor across its coil is adjusted so that the plate current flowing through the coil when the thermionic time-delay tube 28 or 28' attains normal electron emission is the minimum value required for operation. If the variable resistor across the coil of the relay is adjusted so that the plate current flowing through the coil when the thermionic time-delay tube attains normal electron emission is greater than the minimum value required for operation, the minimum value of plate current flows sooner than before through the coil, causing operation of the relay, the greater the plate current flowing through the coil when the thermionic time-delay tube attains normal electron emission, the sooner the minimum value of plate current required to operate the relay is reached.

In Figures 1, 2, 3, 4, 5, and 6, the variable resistor 33 shunted across the coil of relay 17 or safety relay 26 may therefore be used to regulate the flow of plate current through the coil and thereby to control the time of operation of the relay, as mentioned previously above.

Also, in Figures 1, 2, 3, 4, 5, and 6, condenser 25 shunted across the coil of safety relay 26, and condenser 25' shunted across the coil of relay 17, prevent chattering of the armature when A. C. voltage is applied to the plate of the thermionic time-delay tube 28 or 28' respectively, or to the plate of one of the thermionic vacuum tubes 2 subjected to rapid cathode heating when relay 17 is connected in its plate circuit.

In Figures 1 to 6 inclusive, the voltage at the voltage supply circuit terminals 6 and 7 is A. C., allowing the use of transformers and voltage-dropping resistors to provide the proper values of filament or heater voltage for the thermionic vacuum tubes. The voltage at the voltage supply circuit terminals 6 and 7 may also be D. C., voltage-dropping resistors being employed where necessary to provide the proper values of filament or heater voltage for the thermionic vacuum tubes.

Although I have described my invention with

a certain degree of particularity, it is understood that various changes or modifications may be made within the scope of the claims hereto attached without departing from the spirit of the invention.

What I claim is:

1. In electron discharge apparatus, the combination of thermionic vacuum tubes of the indirectly heated cathode type provided with two heaters within the metallic cathode sleeve, one set of heaters connected in series used for rapid cathode heating and the other set connected in parallel used for normal cathode heating, and means for applying voltage to both sets of heaters of said thermionic vacuum tubes for rapid cathode heating until normal electron emission is attained and for applying voltage thereafter only to the set of heaters of said thermionic vacuum tubes used for normal cathode heating.

2. In electron discharge apparatus, the combination of thermionic vacuum tubes of the indirectly heated cathode type provided with two heaters within the metallic cathode sleeve, one used for rapid cathode heating and the other for normal cathode heating, and means comprising a relay connected in the plate circuit of a thermionic time-delay tube for applying voltage to both heaters of said thermionic vacuum tubes for rapid cathode heating until normal electron emission is attained and for applying voltage thereafter only to the heater of said thermionic vacuum tubes used for normal cathode heating.

3. In electron discharge apparatus, the combination of thermionic vacuum tubes and relay means connected in the plate circuit of one of said thermionic vacuum tubes for applying greater than normal voltage to the heating elements of said thermionic vacuum tubes for rapid cathode heating until normal electron emission is attained and for applying normal voltage to the heating elements of said thermionic vacuum tubes thereafter for normal cathode heating, and means comprising a thermionic time-delay relay which stops rapid cathode heating when normal electron emission is attained by said thermionic vacuum tubes if the first mentioned relay means fails to perform this function, to prevent damage to said thermionic vacuum tubes.

4. In electron discharge apparatus, the combination of thermionic vacuum tubes and means comprising a relay connected in the plate circuit of a thermionic time-delay tube for applying greater than normal voltage to the heating elements of said thermionic vacuum tubes for rapid cathode heating until normal electron emission is attained and for applying normal voltage to the heating elements of said thermionic vacuum tubes thereafter for normal cathode heating, and means comprising a thermionic time-delay relay which stops rapid cathode heating when normal electron emission is attained by said thermionic vacuum tubes if the first mentioned relay means fails to perform this function, to prevent damage to said thermionic vacuum tubes.

5. In electron discharge apparatus, the combination of thermionic vacuum tubes of the indirectly heated cathode type and relay means connected in the plate circuit of one of said thermionic vacuum tubes for applying greater than normal voltage to the heaters of said thermionic vacuum tubes for rapid cathode heating until normal electron emission is attained and for applying normal voltage to the heaters of said thermionic vacuum tubes thereafter for nor-

mal cathode heating, and means comprising a thermionic time-delay relay which stops rapid cathode heating when normal electron emission is attained by said thermionic vacuum tubes if the first mentioned relay means fails to perform this function, to prevent damage to said thermionic vacuum tubes.

6. In electron discharge apparatus, the combination of thermionic vacuum tubes of the indirectly heated cathode type and relay means connected in the plate circuit of one of said thermionic vacuum tubes for applying greater than normal voltage to the filaments of said thermionic vacuum tubes for rapid heating until normal electron emission is attained and for applying normal voltage to the filaments of said thermionic vacuum tubes thereafter for normal heating, and means comprising a thermionic time-delay relay which stops rapid filament heating when normal electron emission is attained by said thermionic vacuum tubes if the first mentioned relay means fails to perform this function, to prevent damage to said thermionic vacuum tubes.

7. In electron discharge apparatus, the combination of thermionic vacuum tubes of the indirectly heated cathode type provided with two heaters within the metallic cathode sleeve, one used for rapid cathode heating and the other for normal cathode heating, and relay means connected in the plate circuit of one of said thermionic vacuum tubes for applying voltage to both heaters of said thermionic vacuum tubes for rapid cathode heating until normal electron emission is attained and for applying voltage thereafter only to the heater of said thermionic vacuum tubes used for normal cathode heating, and means comprising a thermionic time-delay relay which stops rapid cathode heating when normal electron emission is attained by said thermionic vacuum tubes if the first mentioned relay means fails to perform this function, to prevent damage to said thermionic vacuum tubes.

8. In electron discharge apparatus, the combination of thermionic vacuum tubes of the indirectly heated cathode type and means comprising a relay connected in the plate circuit of a thermionic time-delay tube for applying greater than normal voltage to the heaters of said thermionic vacuum tubes for rapid cathode heating until normal electron emission is attained and for applying normal voltage to the heaters of said thermionic vacuum tubes thereafter for normal cathode heating, and means comprising a thermionic time-delay relay which stops rapid cathode heating when normal electron emission is attained by said thermionic vacuum tubes if the first mentioned relay means fails to perform this function, to prevent damage to said thermionic vacuum tubes.

9. In electron discharge apparatus, the combination of thermionic vacuum tubes of the indirectly heated cathode type and means comprising a relay connected in the plate circuit of a thermionic time-delay tube for applying greater than normal voltage to the filaments of said thermionic vacuum tubes for rapid heating until normal electron emission is attained and for applying normal voltage to the filaments of said thermionic vacuum tubes thereafter for normal heating, and means comprising a thermionic time-delay relay which stops rapid filament heating when normal electron emission is attained by said thermionic vacuum tubes if the

first mentioned relay means fails to perform this function, to prevent damage to said thermionic vacuum tubes.

10. In electron discharge apparatus, the combination of thermionic vacuum tubes of the indirectly heated cathode type provided with two heaters within the metallic cathode sleeve, one used for rapid cathode heating and the other for normal cathode heating, and means comprising a relay connected in the plate circuit of a thermionic time-delay tube for applying voltage to both heaters of said thermionic vacuum tubes for rapid cathode heating until normal electron emission is attained and for applying voltage thereafter only to the heater of said thermionic vacuum tubes used for normal cathode heating, and means comprising a thermionic time-delay relay which stops rapid cathode heating when normal electron emission is attained by said thermionic vacuum tubes if the first mentioned relay means fails to perform this function, to prevent damage to said thermionic vacuum tubes.

11. In electron discharge apparatus, the combination of thermionic vacuum tubes and relay means connected in the plate circuit of one of said thermionic vacuum tubes for applying greater than normal voltage to the heating elements of said thermionic vacuum tubes for rapid cathode heating until normal electron emission is attained and for applying normal voltage to the heating elements of said thermionic vacuum tubes thereafter for normal cathode heating, and means comprising a thermionic time-delay relay supplied with current directly from the voltage supply circuit which stops rapid cathode heating when normal electron emission is attained by said thermionic vacuum tubes if the first mentioned relay means fails to perform this function, to prevent damage to said thermionic vacuum tubes.

12. In electron discharge apparatus, the combination of thermionic vacuum tubes and means comprising a relay connected in the plate circuit of a thermionic time-delay tube for applying greater than normal voltage to the heating elements of said thermionic vacuum tubes for rapid cathode heating until normal electron emission is attained and for applying normal voltage to

the heating elements of said thermionic vacuum tubes thereafter for normal cathode heating, and means comprising a thermionic time-delay relay which stops rapid cathode heating when normal electron emission is attained by said thermionic vacuum tubes if the first mentioned relay means fails to perform this function, to prevent damage to said thermionic vacuum tubes, both said relay means supplied with current directly from the voltage supply circuit.

13. In electron discharge apparatus, the combination of thermionic vacuum tubes and relay means connected in the plate circuit of one of said thermionic vacuum tubes for applying greater than normal voltage to the heating elements of said thermionic vacuum tubes for rapid cathode heating until normal electron emission is attained and for applying normal voltage to the heating elements of said thermionic vacuum tubes thereafter for normal cathode heating, and means comprising a thermionic time-delay relay which stops rapid cathode heating when normal electron emission is attained by said thermionic vacuum tubes if the first mentioned relay means fails to perform this function, to prevent damage to said thermionic vacuum tubes, and a variable resistor shunted across the relay coil to adjust the time of operation of said latter relay means.

14. In electron discharge apparatus, the combination of thermionic vacuum tubes and means comprising a relay connected in the plate circuit of a thermionic time-delay tube for applying greater than normal voltage to the heating elements of said thermionic vacuum tubes for rapid cathode heating until normal electron emission is attained and for applying normal voltage to the heating elements of said thermionic vacuum tubes thereafter for normal cathode heating, and means comprising a thermionic time-delay relay which stops rapid cathode heating when normal electron emission is attained by said thermionic vacuum tubes if the first mentioned relay means fails to perform this function, to prevent damage to said thermionic vacuum tubes, and a variable resistor shunted across each relay coil to adjust the time of operation of both said relay means.

ISADOR WARSHAWSKY.
